US00D871797S

(12) **United States Design Patent** (10) **Patent No.:** **US D871,797 S**
Chen (45) **Date of Patent:** **** Jan. 7, 2020**

(54) **NECK PILLOW**

(71) Applicant: **SHENZHEN LIAN DA
TECHNOLOGY INDUSTRIAL CO.,
LTD.**, Shenzhen, Guangdong (CN)

(72) Inventor: **Congyu Chen**, Guangdong (CN)

(73) Assignee: **SHENZHEN LIAN DA
TECHNOLOGY INDUSTRIAL CO.,
LTD.**, Shenzhen (CN)

(**) Term: **15 Years**

(21) Appl. No.: **29/655,546**

(22) Filed: **Jul. 5, 2018**

(51) LOC (12) Cl. **06-09**

(52) U.S. Cl. **D6/601**
USPC ....

Primary Examiner — Michelle E. Wilson
Assistant Examiner — Sanjeev Paul

(57) **CLAIM**

The ornamental design for a neck pillow, as shown and described.

DESCRIPTION

FIG. 1 is a front perspective view of a neck pillow showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

1 Claim, 8 Drawing Sheets
